United States Patent

Des. 235,338
Patented June 10, 1975

235,338

TEXTILE BOBBIN

Arthur C. Hamilton, 53 Fenley Drive,
Weston, Ontario, Canada

Filed Feb. 14, 1973, Ser. No. 332,357

Term of patent 14 years

Int. Cl. 15—06

U.S. Cl. D19—15

FIG. 1

FIG. 2

FIG. 3

FIG. 1 is a side plan view of a frusto-conical textile bobbin showing my new design which has a plurality of alternate equal width ridge sections and groove sections encircling its conical surface and all sides are identical to that shown;

FIG. 2 is a top plan view thereof; and

FIG. 3 is an enlarged fragmentary side view of a ridge section and two neighboring groove sections thereof showing that each ridge section has six micro-grooves and each groove section also has six micro-grooves.

I claim:

The ornamental design for a textile bobbin, as shown and described.
